UNITED STATES PATENT OFFICE.

ALBERT POCHELON, OF DETROIT, MICHIGAN.

DESIGN FOR AN AUTOMOBILE RADIATOR ORNAMENT OR SIMILAR ARTICLE.

Application filed November 9, 1927. Serial No. 24,055. Term of patent 7 years.

To all whom it may concern:

Be it known that I, ALBERT POCHELON, a citizen of the United States, and resident of the city of Detroit, county of Wayne, and State of Michigan, have invented a new, original, and ornamental Design for an Automobile Radiator Ornament or Similar Article, of which the following is a specification, reference being had to the accompanying drawing, forming a part thereof.

Fig. 1 is a front elevation of the automobile radiator ornament.

Fig. 2 is a side elevation of the left side of the automobile radiator ornament.

Fig. 3 is a rear elevation of an automobile radiator ornament or similar article.

Fig. 4 is a side elevation of the right side of an automobile ornament or similar article.

What I claim is:

The ornamental design for an automobile radiator ornament or similar article as shown.

ALBERT POCHELON.
